TOP ROLL LOADING DEVICE

Leland D. Cobb, Forestville, Conn., assignor to
 General Motors Corporation, Detroit, Mich., a
 corporation of Delaware

Application January 2, 1942, Serial No. 425,416

20 Claims. (Cl. 19—135)

This invention relates to top roll loading devices as used in drawing, roving, spinning and other textile machines, and particularly to a pressure applying mechanism for distributing downward pressures to a plurality of top rolls.

An object of this invention is to provide an improved and simplified device for applying and distributing pressures to a plurality of top rolls. A further object is to provide a pressure applying mechanism for a plurality of top rolls and which distributes a loading pressure to the end portions of one top roll and to the central portions of the other top rolls. Another object is to provide a loading mechanism and top roll construction wherein rotatable friction is eliminated between the loading mechanism and the top rolls.

To these ends and also to improve generally upon devices of the character indicated, the invention consists in the various matters hereinafter described and claimed.

In the accompanying drawings:

Figure 1 is a fragmentary perspective view showing the application of my pressure loading mechanism;

Figure 2 is an end view of a conventional spinning frame and showing one embodiment of my loading mechanism;

Figure 3 is an enlarged plan view of the parts shown in Figure 2;

Figures 4 and 5 are fragmentary views in longitudinal section through top rolls particularly adapted for use with my loading mechanism; and

Figure 6 is a fragmentary perspective view showing another embodiment of my loading mechanism.

My invention is illustrated in connection with parts of a spinning frame wherein a roller beam 10 supports a plurality of roll stands, one of which is designated at 11. Each roll stand provides bearings for rotatably supporting a plurality of bottom rolls 12, 13 and 14 which are suitably rotatably driven by mechanism not shown. In accordance with usual practice, front, middle and rear top drawing rolls 15, 16 and 17 have their reducing outer ends loosely received in non-bottoming relation within guide slots 18 in cap bars 20 pivoted at their rearward ends to a cross rod 22 supported by the roll stands 11, and these guide slots 18 locate the top rolls respectively in peripherally supported rolling engagement with the corresponding bottom rolls therebeneath. Strips of yarn, thread or other suitable strips of intermingled fibers, as S, are fed be-

tween the rotating top and bottom rolls to produce a desired attenuating operation, and the pressures exerted upon these strips S by the successive sets of rolls are controlled by my loading mechanism.

One form of my front top roll 15 is illustrated in Fig. 5, wherein a sleeve 24 is rotatably supported at its ends through ball bearings 25 on a stationary shaft 26. The sleeve 24 has an intermediate necked portion 27, and cots 28 of suitable yieldable material are fastened over the sleeve ends for operative rolling engagement with the strips S and with corresponding roll portions R on the bottom roll 12 therebeneath. A collar 29, demountably held in position on each end of the shaft 26, as by a dog point set screw 30, serves to hold the top roll parts in unit-handling assembled relation and has a necked outer end 32 which loosely fits in the slot 18 to vertically 10 guide this top roll 15. These necked ends 32 are non-rotatably engaged by my loading device in a manner to be described.

One form of my middle and rear top rolls 16 and 17 is illustrated in Fig. 4, wherein a rotatable shaft 34 has spaced roll members 35 covered with suitable cots 36 that rotatably engage both the strips S and the correspondingly positioned roll portions R on the bottom rolls 13 and 14. These roll members 35 are demountably 20 secured to the ends of the shaft 34, as by dog point set screws 37 threaded in the necked outer ends 38 of the roll members, and the necked ends 38 are loosely and vertically guided by the slots 18. A counterbore in the inner end of each roll 30 member 35 frictionally receives and supports the outer race ring of a ball bearing 40 which has a freely rotatable inner race ring surrounding the shaft 34 in spaced relation. These inner race 35 rings, which axially extend beyond the outer race 40 rings and towards each other, co-operatively support a sleeve 41 that is non-rotatably engaged by my loading mechanism as will appear.

My pressure loading mechanism includes a generally T-shaped saddle 42 provided with a cross bar 43 from which a shank 44 extends rearwardly and substantially at right angles. The cross bar 43, which is substantially horizontally disposed forwardly of and above the front top roll 15, has its ends bent rearwardly and downwardly to provide roller engaging arms 45, the ends of these arms being shaped to provide stepped portions 46 that rest upon and fit over the necked ends 32 of the top roll 15 as best illustrated in Fig. 1. Each stepped portion 46 includes a downwardly extending tongue 47 which

overlies the outer end of the collar 29. This tongue 47 loosely fits within the groove 18 and is offset from the arm 45 by a horizontally disposed foot 48 arcuately curved to substantially matingly seat upon the necked outer end 32 of the collar 29 so that downward pressure applied on the saddle 42 will be transmitted to the outer ends of the front top roll 15 to urge this top roll with desired pressure into supported rolling contact with the corresponding bottom roll 12. With this construction, the ball bearings 25 provide substantially frictionless rotation of the top roll sleeve 24 about the shaft 26 which does not rotate, and the end collars 29 will non-rotatably engage the stepped portions 46 and will be non-rotatably received in the guide slots 18.

Fig. 6 shows an alternative construction for the stepped portions 46 on the ends of the cross bar 43. In this form of my invention, downwardly and rearwardly extending arms 45 corresponding to the arms 45 each terminate in a foot 46 provided with an arcuate face 148 that substantially matingly seats in a peripheral groove 149 cut in the necked end of the collar 29. I preferably interrupt the face 148 with a groove 150 so that the foot 46 will not rock on the collar 29 in the event of an improper seated relation of the face 148 in the groove 149.

The rearward end of the shank 44 tiltably and slidably seats in a longitudinally disposed groove 50 formed in the upper portion of a rear saddle 52 provided at its rearward end with a yoke 53 seated upon the sleeve 41 between the roll members 35 of the rear top roll 17, and the forward end of this saddle 52 has a foot 54 that rests upon the corresponding sleeve 41 of the middle top roll 16. To laterally position the saddle 52, I may provide a depending portion within the yoke 53 which seats in a peripheral groove 55 cut in the sleeve 41 of the rear top roll 17. If desired, this groove 55 may be eliminated and the yoke 53 may be freely slidably axially of the sleeve 41 in which event both saddles 42 and 52 will be laterally positioned by the stepped portions 46. The ball bearings 40 in the middle and rear top rolls 16 and 17 facilitate free rotation of the roll members 35 about the sleeves 41 which non-rotatably engage the saddle member 52.

Downward pressure is applied through my loading mechanism and distributed to all of the top rolls through the co-operating saddle members 42 and 52 by a stirrup 56 which is U-shaped in cross section and which has a bifurcated hook-shaped upper end 57 in straddling relation to the saddle members and is loosely pivoted by a pin 58 to the shank 44. This pin location is preferably so located from the shank 44 that greater pressure will be delivered to the front top roll 15 than to the middle and rear top rolls 16 and 17. An amplifying lever 59 has a hooked forward end fulcrumed in a vertically adjustable eye 60 secured to the roller beam 10. This lever 59 passes through and rests upon the bottom of a slot 61 in the stirrup 56, and a weight or other suitable means acts through a link 62 to pull downwardly on the rearward end of the lever 59 to exert the required downward pressure on the stirrup 56.

Occasionally the strips of thread S or the like which are passed between the sets of top and bottom rolls have uneven portions, and my loading device facilitates individual tilting and individual vertical movements of the top rolls with respect to each other while maintaining the desired downward pressures on each of the top rolls. To accomplish this, the longitudinal slot 50 is 75

made much wider than the rearward end of the shank 44 which is preferably provided with a rounded lower edge 63 to facilitate a relative lateral tilting movement between the saddle members. The pin 58 is loosely mounted in the shank 44 so that it will not restrict this lateral tilting movement, and the arms forming the bifurcated hooked upper end 57 of the stirrup are spaced sufficiently so as to permit this lateral tilting movement. The slot 50 may also have a high point intermediate of its ends so that the shank 44 will be free to longitudinally tilt and permit an up and down movement of the front top roll 15 relative to the other top rolls without changing its fulcrum point. The middle and rear top rolls 16 and 17 may individually tilt and individually move up and down since the saddle 52 tiltably rests on the sleeve members 41.

I claim:

1. A pressure applying mechanism for a plurality of spaced top rolls comprising a pair of connected load applying members respectively resting on the opposite ends of one of said top rolls, another load applying member bearing on at least one of said other top rolls, and weight applying means distributing downward pressures to all of said load applying members.

2. A pressure applying mechanism for a plurality of spaced top rolls comprising a pair of interconnected load applying members respectively resting on the opposite ends of one of said top rolls, another load applying member bearing on the intermediate portions of at least one of said other top rolls, and weight applying means simultaneously distributing downward loading pressure to all of said load applying members.

3. A pressure applying mechanism for a plurality of spaced top rolls comprising a pair of saddles, one of said saddles having end portions respectively seated in mating relation on the opposite ends of one of said top rolls, said other saddle bearing on an intermediate portion of at least one of said other top rolls, and means distributing downward pressure in both of said saddles.

4. A pressure applying mechanism for a plurality of top rolls comprising a pair of saddles, one of said saddles resting on an intermediate portion of one of said top rolls, said other saddle resting on the opposite end portions of another of said top rolls and upon said first mentioned saddle, and means applying a downward pressure to said other saddle.

5. In a pressure applying mechanism for a plurality of spaced top rolls having reduced rounded ends, a front saddle longitudinally straddling one of said top rolls, laterally extending arms on the saddle and seated on the reduced rounded ends of said top roll, a rear saddle bearing upon the intermediate portion of at least one of said other top rolls, and means for simultaneously applying downward pressure to each of said saddles.

6. A pressure applying mechanism for a plurality of spaced top rolls comprising a saddle, spaced roll engaging portions on said saddle and supported on the opposite ends of one of said top rolls, a second saddle provided with a roll engaging member supported on a central portion of one of said other top rolls, a shank on said first mentioned saddle and bearing on said second saddle, and downward pressure applying means engaging said shank.

7. A pressure loading mechanism for a plurality of rolls comprising a saddle, a cross arm on said saddle and having end portions resting on

the opposite end portions of one of said rolls, a second saddle, end portions of said second saddle respectively resting on intermediate portions of two of said other rolls, a shank extending rearwardly from said cross arm and resting on the second saddle, and downwardly applying pressure means engaging said shank.

8. A pressure applying mechanism for a plurality of top rolls comprising a pair of saddle members, one of said saddle members having end portions respectively supported on central portions of two of said top rolls, a cross arm on said other saddle member, laterally projecting arms on the cross arm and having end seating portions fitting over the opposite end portions of one of said other top rolls, a shank extending outwardly from an intermediate portion of said cross arm, said first mentioned saddle having a groove which tiltably receives and supports the free end of said shank, and weight applying means connected to said shank.

9. A pressure loading mechanism for a plurality of top rolls comprising a pair of saddle members, one of said saddle members having a foot resting on the central portion of one of the top rolls, a cross arm on said other saddle member and having end portions matingly seated on the opposite end portions of one of said other top rolls, a shank extending outwardly from the cross arm, said first mentioned saddle having a depressed portion which supports a portion of said shank for tilttable movement transversely and longitudinally of the shank, and weight applying means connected to said shank.

10. A pressure loading mechanism for a plurality of spaced top rolls comprising a pair of saddle members, end portions on one of said saddle members respectively resting on intermediate portions of two of said top rolls, said other saddle member being substantially T-shaped with a rearwardly extending shank tiltably resting on said first mentioned saddle member, end portions on the T-shaped saddle member respectively seated on the opposite ends of another of said top rolls, and weighting means urging said shank downwardly.

11. A pressure loading mechanism for a plurality of spaced top rolls comprising a saddle having a cross arm, load applying members on the cross arm and matingly seated on the opposite ends of one of said top rolls, a second saddle having a foot tiltably resting on an intermediate portion of another of said top rolls, a shank extending outwardly from said cross arm and tiltably resting at one end on said second saddle, a stirrup pivotably connected to said shank, and weighting means connected to said stirrup.

12. In a mechanism of the character described, the combination with a plurality of pairs of top and bottom rolls, the individuals of each pair being mounted one above the other and means supporting said pairs of rolls to operate successively on a strip of intermingled fibers fed between them, of a T-shaped saddle including a cross arm, end portions on the cross arm shaped to overlie and matingly seat on the opposite end portions of the front top roll, a second saddle bearing on two of said other top rolls, and means for simultaneously applying downward pressure to both of said saddles.

13. In a pressure loading mechanism for a plurality of spaced top rolls having reduced cylindrical ends, a saddle, a cross arm on said saddle, arcuate end faces on said cross arm matingly seated on the opposite reduced ends of one of

said top rolls, a second saddle resting on the intermediate portions of two of said other top rolls, and means applying downward pressure to both of said saddles.

14. In a pressure applying mechanism for a plurality of spaced top rolls having reduced cylindrical ends, a saddle, stepped end portions on the saddle respectively fitting over and supported on the opposite reduced ends of one of said top rolls, a second saddle resting on at least one of said other top rolls, and means simultaneously applying downward pressure to both of said saddles.

15. In a pressure loading mechanism for a plurality of spaced top rolls having reduced cylindrical ends, a saddle having a cross arm, stepped end portions on the cross arm and respectively overlying the reduced cylindrical ends on one of said rolls, each of said stepped end portions including a curved portion seated on one of said cylindrical ends and a downwardly extending tongue overlying said cylindrical end, a second saddle member resting on at least one of said other top rolls, and means applying downward pressure to both of said saddle members.

16. A pressure loading device for simultaneously applying downward pressure to the front, middle and rear top rolls in a spinning frame comprising a T-shaped front saddle, end arms on said saddle resting on the opposite ends of the front top roll, a rear saddle supported by the central portions of the middle and rear top rolls, a rearwardly extending shank on said front saddle and having a rearward end supported on said rear saddle, and pressure applying means including a stirrup extending upwardly between said middle and rear top rolls, said stirrup having a hook-shaped upper end pivotably connected to said shank between the front and middle top rolls.

17. In a drawing mechanism of the character described, the combination with a plurality of pairs of top and bottom drawing rolls, the individuals of each pair being mounted one above the other for successive drawing operations on a thread, of a T-shaped saddle including a cross arm having laterally projecting end portions seated on the opposite end portions of the front top roll, a rear saddle bearing on two of said top rolls, a shank on said T-shaped saddle secured at its forward end to said cross arm and having a rearward end resting on said rear saddle, a stirrup having a bifurcated hook-shaped upper end straddling said shank and said rear saddle, a pivotal connection between the upper end of said stirrup and said shank, and weight applying means secured to the lower end of said stirrup.

18. A top roll loading device for distributing downward pressure to front, middle and rear spaced top rolls as used in a spinning machine, the front roll having non-rotatable reduced ends and the other rolls having non-rotatable intermediate necked portions, said loading device comprising a substantially T-shaped saddle provided with a cross arm, a shank extending laterally from said cross arm above the intermediate portions of said top rolls, end portions of said cross arm matingly seated on the opposite reduced ends of the front top roll, a second saddle supported at its ends on the intermediate necked portions of the middle and rear top rolls, said second saddle tiltably supporting the rearward end of said shank, and a weighting mechanism

including a stirrup pivoted at its upper end to said shank.

19. In a drawing mechanism of the character described, the combination with a plurality of pairs of drawing rolls, the individuals of each pair being mounted one above the other and means supporting said rolls to operate successively on a sliver fed between them, of a T-shaped saddle including a bar having end portions resting on opposite end portions of the front top roll, a second saddle member bearing on one or more of said rear top rolls, the shank of said T-shaped saddle bearing on said second saddle member, and means connected with said shank to apply weight to said saddle and therethrough to said top roll and to said second saddle member.

20. In a drawing mechanism of the character described, the combination with a plurality of

pairs of drawing rolls, the individuals of each pair being mounted one above the other and means supporting said rolls to operate successively on a sliver fed between them, of a T-shaped saddle including a bar having end portions resting on opposite end portions of the front top roll, a second saddle member bearing on one or more of said rear top rolls, the shank of said T-shaped saddle bearing on said second saddle member, and means connected with said shank to apply weight to said saddle and therethrough to said top roll and to said second saddle member.

LELAND D. CORE.
